UNITED STATES PATENT OFFICE

163,491

COVERED PITCHER

Carlyle B. Stair, Glendale, Calif.

Application December 30, 1950, Serial No. 13,636

Term of patent 3½ years

(Cl. D44—21)

To all whom it may concern:

Be it known that I, Carlyle B. Stair, a citizen of the United States, residing at Glendale, California, have invented a new, original, and ornamental Design for Covered Pitcher, of which the following is a specification, reference being had to the accompanying drawing, which forms a part thereof and in which drawing:

Fig. 1 is a side perspective view of a covered pitcher embodying my new design, the view being taken from a point slightly above the upper surface of the pitcher; and

Fig. 2 is a top plan view of the pitcher shown in Fig. 1.

I claim:

The ornamental design for a covered pitcher, substantially as shown.

CARLYLE B. STAIR.
